GARMENT

Elmer W. Levi, Camden, N. J.

Application March 7, 1952, Serial No. 275,270

3 Claims. (Cl. 2—74)

1

This invention relates to a garment, and more particularly concerns an article of wearing apparel such as a lady's dress or the like having an apparel closure and removable and replaceable fastening means therefor.

Conventional articles of apparel such as dresses and the like have heretofore been difficult to launder or dry clean without damaging the buttons or fasteners therefor. Since the buttons are conventionally sewed to the garment material it has been a time consuming task to remove them for purposes of cleaning and then to sew them back on the garment after cleaning. Moreover the garment material is often worn or damaged upon repeated removal and replacement of buttons in this matter.

Accordingly it is one object of this invention to provide means whereby buttons and other fasteners may readily be applied to and removed from a garment. Another object is to facilitate the removal of buttons or other fasteners from a garment in one operation without damaging the garment material.

Conventional dresses are often made of relatively light weight material and have relatively heavy buttons affixed thereto. However the heavy buttons often tend to pull the inner layer of fabric forwardly through the buttonholes, thereby detracting from the appearance of the garment and tending to pull and distort or damage the material thereof. It is accordingly another object of this invention to provide a garment including a closure means particularly adapted for use in connection with relatively light weight material which is free of the foregoing objections.

Other objects and advantages of this invention, including the simplicity and economy of the same, as well as the ease with which different sets of buttons may be applied interchangeably to a garment for ornamental or other purposes, will further become apparent hereinafter and in the drawings whereof:

Fig. 1 represents a front view of one specific embodiment of this invention shown as applied to a lady's dress, with the lower portion of the dress shown unbuttoned in order more clearly to show important details;

Fig. 2 represents an enlarged fragmentary view similar to Fig. 1, taken as indicated by the area enclosed in the dot-dash lines II which appear in Fig. 1;

Figs. 3 and 4 represent sectional views taken as indicated by the lines and arrows III—III and IV—IV which appear in Fig. 2; and

Fig. 5 represents a view in front elevation show-

2

ing one specific form of fastening element constituting one element of the article shown in Figs. 1—4.

Turning now specifically to the drawings, the number 10 designates a lady's dress which comprises a piece of flexible material including an outer panel 11 and an inner panel 12, which panels are separable from one another to provide a frontal opening for the dress 10. Formed in the outer panel 11 are a plurality of equally spaced eyelets 13 each of which defines an elongate buttonhole 14 which has a longitudinal axis that extends substantially horizontally of the outer panel 11. Formed in the inner panel 12 are a plurality of eyelets 15 which define a plurality of equally spaced elongate buttonholes 16 the longitudinal axes of which extend substantially vertically of the inner panel 12. The buttonholes 14, 16 are equally spaced and are constructed and arranged on their respective panels 11, 12 to form registered pairs when the panels 11, 12 are overlapped to form a closure for the dress. The outer and inner panels 11, 12 are disposed immediately adjacent to one another in parallel face to face relation throughout the dress closure area but are separated from one another at 17 to form a throat opening for the dress.

The number 20 designates a piece of flexible material preferably in the form of a tape to which a plurality of buttons 21 are affixed. The buttons 21 are spaced apart from one another corresponding to the spacing between the pairs of buttonholes 14, 16. The buttons 21 are preferably fixed to the tape by stitches 22 (Figs. 3, 4) but

35 may of course be otherwise affixed by other conventional fastening means. As shown in the drawings the buttons 21 have integral shanks 23 which extend through the registered buttonholes, said shanks 23 being thick enough to spread apart the eyelets 13, 15 and locally enlarge the buttonholes 14, 16.

40 At its upper end which is adjacent to the throat opening 17, the tape 20 is of V-formation and is accordingly readily concealed beneath the throat opening. The tape 20 includes a stiffener element 24 which extends from the top of the tape 20 to a point below the uppermost button 21a which is the anchor button. It preferably terminates at edge 26 just above the stitches 22 of the button 21 which is immediately below the anchor button 21a.

45 It will be appreciated that the dress closure is readily completed by disposing the tape 20 immediately adjacent to the inner face of the inner panel 12 and projecting the buttons and button

55

fastening means through the registered pairs of buttonholes 14, 16. Preferably the buttonholes are arranged on their respective panels in such manner that the lower corner of each vertical buttonhole 16 registers with that corner of the corresponding horizontal buttonhole 14 which is nearest to the edge 25 of the outer panel 11. In use the maximum strain is generally applied to the uppermost button 21a which is accordingly termed the anchor button, and this button 21a is effectively prevented from pulling through the corresponding buttonholes 14, 16 by the stiffener element 24 which may consist of the same material as tape 20, folded back upon itself and sewed in this position. However the stiffener element 24 may of course consist of buckram or other cloth or any other stiffening means such as whalebone, for example, and may be affixed to the tape 20 in any desired manner. These buttons below the anchor button 21a are subjected to much less stress than is applied to the anchor button, and the stiffening means 24 accordingly preferably terminates at 26 above the button 21 which is disposed immediately below the anchor button 21a. The single layer of tape 20 below the termination 26 is highly preferred for the sake of comfort, flexibility and economy.

It will be appreciated that the particular construction wherein the registered buttonholes are disposed at angles to one another is of particular advantage in that interlocking supporting means are thereby provided, which are effective in two different directions and serve as positive supports for the button element which passes through the buttonholes. This minimizes the stretching and distortion of the material of panels 11, 12 and is particularly advantageous when a relatively light garment panel material is utilized in combination with relatively heavy buttons or other fasteners.

While I have shown and described the particularly preferred combination wherein one set of buttonholes is horizontal and the other set of buttonholes is vertical, it will be appreciated that other angular arrangements may be utilized if desired. Moreover while the buttonholes have been illustrated as registering at or near their extreme ends, it will be appreciated that many of the advantages of this invention are realized by registering the buttonholes at points other than their ends. However particular advantage is attained with the longitudinal axes of the horizontal buttonholes disposed substantially in line with lower ends of the corresponding vertical buttonholes. This gives particularly effective support for the buttons or other fastening means.

While this invention has been illustrated as particularly applied to the frontal opening of a dress, it will be appreciated that it is also applicable to closures for sleeves and other portions of garments generally. Buttons other than the ones specifically illustrated in the drawings may be employed, and they may or may not include relatively thick shanks or shanks of any kind since stitching or other fastening means adapted

to extend through the registered buttonholes will suffice to secure the parts together in the manner of this invention. Moreover fastening means other than buttons may be utilized in the combination described, without departing from the scope of this invention.

While I have shown and described in detail the article of apparel constituting one form of my invention, it will be appreciated that modifications may be made in the form of the apparel and the closure therefor, including reversals of parts, substitutions of equivalents, and the use of certain parts independently of others, all within the spirit and scope of the invention as defined in the appended claims.

Having thus described my invention, I claim:

1. A dress comprising a piece of material including outer and inner panels of relatively light weight material each having a plurality of equally spaced elongate buttonholes therein, the longitudinal axis of one set of said buttonholes being disposed at an angle to the longitudinal axis of the other set of said buttonholes, said sets of buttonholes being arranged on their respective panels to lie next to one another with the ends of one set of said buttonholes registered with the ends of the other set of said buttonholes, a tape, a plurality of buttons extending from the top of the bottom of said tape, fastening means extending between said buttons and said tape securing said buttons in spaced relation to said tape, the buttons being equally spaced in accordance with the spacing of said buttonholes, said fastening means extending through and contacting one end of the elongate slot of each of said buttonholes, said tape having the top thereof in the form of an inverted V-shape terminating immediately above the uppermost of said buttons, and reinforcing material affixed to the top portion of said tape thereby preventing the upper end of said tape from being drawn through the uppermost buttonholes.

2. The dress defined in claim 1, wherein one of said buttonholes is substantially vertical and the other of said buttonholes is substantially horizontal.

3. The dress defined in claim 2, wherein the substantially vertical buttonhole is disposed on said inner panel and the substantially horizontal buttonhole is disposed on said outer panel.

ELMER W. LEVI.
